(57) **CLAIM**

The ornamental design for a canister portion, as shown and described.

DESCRIPTION

FIG. 1 is a front elevational view of a canister portion, showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top, front, right side isometric view thereof.

The broken lines are for purposes of illustrating unclaimed portions of the canister portion and form no part of the claimed design.
